CONTACT REFRIGERATION UNIT FOR CHILLING DRINKING VESSELS

Richard F. Starrett, P.O. Box 838,
Tiburon, Calif. 94920

Filed Mar. 1, 1974, Ser. No. 447,131

Term of patent 14 years

Int. Cl. D15—07

U.S. Cl. D67—4

FIG. 1

FIG. 2

FIG. 3

FIG. 4

FIG. 5

FIG. 6

FIG. 1 is a view in perspective of a contact refrigeration unit for chilling drinking vessels, incorporating my invention.

FIG. 2 is a view in top plan thereof.

FIG. 3 is a view in bottom plan thereof.

FIG. 4 is a view in end elevation taken from the left side of FIG. 3.

FIG. 5 is a view in side elevation thereof.

FIG. 6 is a view in end elevation taken from the right side of FIG. 3.

I claim:

The ornamental design for a contact refrigeration unit for chilling drinking vessels, substantially as shown.
